(57) **CLAIM**

The ornamental design for a scissors, as shown and described.

DESCRIPTION

FIG. 1 is a front view of a scissors showing my new design;
FIG. 2 is a rear view thereof;
FIG. 3 is a top plan view thereof;
FIG. 4 is a bottom plan view thereof;
FIG. 5 is a right side view thereof;
FIG. 6 is a left side view thereof;
FIG. 7 is an end view of the sectioned part taken along the
arrowed line 7-7 thereof;
FIG. 8 is an end view of the sectioned part taken along the
arrowed line 8-8 thereof; and,
FIG. 9 is a front view thereof showing the opened state.
The broken lines in the drawings illustrate portions of the
scissors which form no part of the claimed design.
